UPRIGHT BABY WALKER

Helen E. Fox, El Paso, Tex.

Application June 20, 1950, Serial No. 169,221

5 Claims. (Cl. 155—22)

1

This invention relates to a mechanism for assisting and inducing a baby to learn to walk.

The object of the invention is to provide an upright walker for babies which will furnish a support for a baby or child learning to walk, and also assist and induce the child to learn to take steps.

Another object of the invention is to provide a baby walker which is constructed as an attractive mechanical toy that includes simulated animals that are actuated for the amusement and fascination of the child as the child pushes the assembly along in learning to walk.

A further object of the invention is to provide a baby walker which is extremely simple and inexpensive to manufacture.

Other objects and advantages of the invention will be apparent during the course of the following description.

In the accompanying drawings forming a part of this application, and in which like numerals are used to designate like parts throughout the same:

Figure 1 is a side elevational view of the baby walker of the present invention;

Figure 2 is a rear elevational view of the baby walker of the present invention;

Figure 3 is a top plan view of the assembly;

Figure 4 is a sectional view taken on the line 4—4 of Figure 2;

Figure 5 is a sectional view taken on the line 5—5 of Figure 1.

Referring in detail to the drawings, the numeral 10 designates a carriage which may be fabricated of any suitable material, such as wood, and the carriage 10 includes a pair of spaced, parallel, vertically disposed side members 11. Extending between the rear ends of the side members 11 is a horizontal disposed rear axle 12, Figure 5. A trunnion 14 projects into each end of the rear axle 12, and a large ground-engaging wheel 15 is connected to each of the trunnions 14.

Extending between the front ends of the pair of side members 11 is a support member 16, the support member 16 being secured to the side members 11 by any suitable means. A trunnion 17 projects into each end of the support member 16, and each of the trunnions 17 serves to support a small ground-engaging front wheel 18. Thus, the carriage is mobile and can be pushed along by a baby or child learning to walk.

Extending upwardly from the side members 11 is a pair of vertically disposed, spaced, parallel uprights 19, the uprights 19 having their

2

lower ends secured to the side members. A horizontally disposed handlebar 20 extends between the upper ends of the uprights 19 and is secured thereto, the handlebar being adapted to be gripped by the baby's hands when the baby walker of the present invention is being used.

Extending between the pair of side members 11 and secured thereto is a bar 21, the bar 21 being arranged forwardly of the rear axle 12. The bar 21 is provided with a plurality of cutouts or slots 22. Extending through each of the cutouts 22 is a lever 24, and pins 23 serve to pivotally connect the levers 24 to the bar 21. Thus, it will be seen that the levers 24 can be made to pivot about a horizontal axis extending through the pins 23.

For causing pivotal movement of the levers 24, a plurality of dowel pins 25 are mounted in the rear axle 12, the ends of the dowel pins 25 projecting beyond the axle 12. These dowel pins 25 are preferably spaced from each other and are arranged at 120-degree angles apart. Thus, as the assembly is pushed along by the child, the wheels 15 rotate to thereby cause rotation of the trunnions 14. The inner ends of the trunnions 14 are secured to the rear axle 12, and the rear axle 12 is rotatably arranged between the side members 11. Thus, rotation of the wheels 15 causes the rear axle 12 to rotate to thereby move the dowel pins 25 into and out of engagement with the rear ends of the levers 24 to thereby cause oscillation or pivotal movement of the levers 24. Mounted on the front end of each of the levers 24 is a toy or body member 26 which preferably has the configuration of an animal, Figure 4. Thus, as the levers 24 are caused to pivot, the animated body members 26 will move up and down to thereby provide a source of amusement and fascination to the child. A bumper 27, which may be fabricated of any suitable material such as rubber, is secured to the lower front surface of each of the levers 24, and the bumpers 27 serve to prevent the front ends of the levers 24 from banging against the support member 16. A back wall 28 extends between the side members 11 and is secured thereto, and a front section 29 is arranged in spaced, parallel relation with respect to the back wall 28, the front section 29 also being secured to the pair of side members 11. A top wall 30 extends between the members 29 and 28, and also between the pair of side members 11, and is secured thereto, so that the members 28, 29 and 30 coact to enclose the rotating dowel pins and other moving parts, so that injury to the child will be pre-

45
50
55

vented, as well as providing an attractive appearance.

In use, the child or baby learning to walk grips the handlebar 20 and is thereby provided with a support. Then, the child pushes the baby walker along the ground or floor, so that the wheels 15 are rotated. This rotation of the wheels 15 causes turning movement of the trunnions 14 which in turn causes rotation of the rear axle 12. As the axle 12 rotates, it causes the dowel pins 25 to move into and out of engagement with the rear ends of the levers 24 to thereby pivot the levers 24 about the pins 23. This pivotal movement of the levers 24 causes up-and-down movement of the toy body members 26 to thereby provide a source of amusement and fascination to the baby as it is learning to walk or take steps.

The baby walker of the present invention will assist the baby in learning to walk by supporting it in a standing position while it is taking its first steps, instead of having the baby sit on a mechanism and push itself around the floor. As the baby pushes the walker of the present invention along by means of the handlebar 20, the three wooden animals 26 are animated or moved up and down by the cam action of the dowel pins 25 which strike the levers 24.

The side members 11 are cut away adjacent the front portions thereof, so that movement of the animals 26 can be observed. Also, the baby walker of the present invention is simple and inexpensive to manufacture. If desired, rubber tires can be added to the wheels, and metal parts can be used for strengthening the various parts of the carriage. The mechanism of the present invention will help to develop and exercise the child's muscles used in walking, and develop its coordination in standing and walking. The bobbing up and down of the animals 26 fascinates the baby, while the walker offers enough support to help him overcome his fear of falling in taking his first steps. The baby walker of the present invention can be painted in any desired colors, and is safe and easy for the baby to handle. The four-wheel support insures that the baby walker will be properly balanced and less likely to tip over and cause the baby to fall.

I claim:

1. In a baby walker, a carriage, wheels supporting said carriage, a pair of spaced, parallel, vertically disposed uprights projecting upwardly from said carriage and secured thereto, a handlebar extending between the upper ends of said uprights and secured thereto, a plurality of levers pivotally supported by said carriage, a body member having the configuration of an animal supported by each of said levers, and means for causing pivotal movement of said levers upon movement of said carriage.

2. In a baby walker, a carriage, wheels supporting said carriage, a pair of spaced, parallel, vertically disposed uprights projecting upwardly from said carriage and secured thereto, a handlebar extending between the upper ends of said uprights and secured thereto, a plurality of levers pivotally supported by said carriage, a body member having the configuration of an animal supported by each of said levers, and means for causing pivotal movement of said levers upon movement of said carriage, said means comprising a rotating axle supported by said carriage and

a plurality of spaced dowel pins projecting from said axle for engagement with said levers.

3. A baby walker comprising a carriage, said carriage including a pair of spaced, parallel side members, a pair of spaced, parallel, vertically disposed uprights projecting upwardly from said side members and secured thereto, a handlebar extending between the upper ends of said uprights and secured thereto, a rotating rear axle extending between said side members, a pair of rear wheels operatively connected to said rear axle, a bar arranged forwardly of said axle and extending between said side members, there being a plurality of spaced cutouts in said bar, a lever extending through each of said cutouts and pivotally connected to said bar, a plurality of spaced dowel pins carried by said axle for engaging said levers and causing pivotal movement thereof, a body member having the configuration of an animal supported on the front end of each of said levers, a support member extending between the front ends of said side members and secured thereto, and a pair of front wheels operatively connected to said support member.

4. A baby walker comprising a carriage, said carriage including a pair of spaced, parallel side members, a pair of spaced, parallel, vertically disposed uprights projecting upwardly from said side members and secured thereto, a handlebar extending between the upper ends of said uprights and secured thereto, a rotating rear axle extending between said side members, a pair of rear wheels operatively connected to said rear axle, a bar arranged forwardly of said axle and extending between said side members, there being a plurality of spaced cutouts in said bar, a lever extending through each of said cutouts and pivotally connected to said bar, a plurality of spaced dowel pins carried by said axle for engaging said levers and causing pivotal movement thereof, a body member having the configuration of an animal supported on the front end of each of said levers, a support member extending between the front ends of said side members and secured thereto, and a pair of front wheels operatively connected to said support member, and a bumper connected to the lower front end of each of said levers to support said support member.

5. The apparatus as described in claim 2 and further including a supporting member forming a part of said carriage and located below the front ends of said levers, and a bumper arranged on the under side of the front end of each of said levers, the bumpers being adapted, during the final phase of the downward movement of the front ends of said levers, to contact said supporting member and thus prevent the banging of the levers against said support member.
